(57) **CLAIM**

The ornamental design for a bond pattern on a filtering face-piece respirator, as shown and described.

DESCRIPTION

FIG. 1 is a perspective view, showing the new design for a bond pattern on a filtering face-piece respirator;

FIG. 2 is a front view thereof;

FIG. 3 is a rear view thereof;

FIG. 4 is a top view thereof;

FIG. 5 is a bottom view thereof; and,

FIG. 6 is a left-side view, the right side view being a mirror image thereof.

The broken line showing forms no part of the claimed design, and the shading is provided to illustrate contour only and is not an indication of texture.
